His Attorney.

UNITED STATES PATENT OFFICE

CHRISTIAN KRÄMER, OF PANKOW, GERMANY, ASSIGNOR TO GENERAL ELECTRIC COMPANY, A CORPORATION OF NEW YORK

ELECTRODE STRUCTURE FOR DISCHARGE DEVICES

Application filed October 27, 1923, Serial No. 671,273, and in Germany January 9, 1923.

The present invention relates to the construction of electrodes for electric discharge devices, as for example, vapor rectifiers.

The cooling of the anodes of high powered rectifiers, particularly mercury arc rectifiers, presents the problem of dissipating large amounts of heat while at the same time maintaining the anodes at a high temperature, preferably at red heat, in order to secure the best operation. Water cooling readily fulfills the first condition, but not the second, and besides has the disadvantage of electrically grounding the anodes. While oil cooling does not have the latter disadvantage, it is capable of maintaining only a slightly higher temperature.

In accordance with my invention I have provided an anode structure which secures the advantage of an efficient, though conducting cooling fluid, such as water, while at the same time securing the advantage of an elevated electrode temperature but avoiding grounding of the electrodes. This improvement is obtained by providing an electrical and thermal insulating layer between an internal cooling device and an exterior heated portion of the anode. This insulating layer conveniently consists of air, or other gas.

The accompanying drawing is a front elevation partly in section of a mercury arc rectifier embodying my invention.

Referring to the drawing the main receptacle 1 is provided with two anodes but one of which is shown in section at 2 projecting into a tubular anode chamber 3 which is welded or otherwise joined to the main receptacle. The anode 2 is insulated from the flange 4 of the anode chamber by an insulator 5. Projecting into the hollow anode but separated therefrom is a hollow cooling device 6. The cooling device is insulated from the anode 2 by a layer of mica 7 or other suitable insulation. For the sake of simplicity, the devices for holding these parts together have not been shown in the drawing. A cooling fluid is supplied by a tube 8 projecting closely adjacent the lower wall of the cooling device 6 and receiving a cooling fluid from a supply pump diagrammatically indicated at 9. A tube 10 discharges the water, or other

cooling fluid to a chamber 11 surrounding the inner and outer wall members occurs only at high temperatures, the outer anode head is made relatively thin walled so that it may be heated rapidly to the desired high temperature. At the same time the sealing flange may then be maintained cool, as a thin walled anode member when heated can only conduct relatively small amounts of heat to the flange. Besides the flange 12 is effectively cooled by the super-imposed flange 13, which is in contact with the cooling fluid.

In order that the heated anode may not be oxidized where it comes in contact with the air, it is preferably protected by a suitable surface treatment, for example, by being alloyed with aluminum or it may be plated with a material which is capable of withstanding a high temperature. The heated anode also may be constructed of two layers so proportioned and arranged that the inner wall does not become highly heated even though the outer wall is at a temperature of incandescence.

The mercury cathode and some other incidental parts of a mercury vapor rectifier have not been shown for the sake of simplicity, but it is to be understood that the described anode may be used in any well known construction and is particularly suitable for high powered rectifiers.

What I claim as new and desire to secure by Letters Patent of the United States, is:

1. A device provided with an anode, means for cooperating therewith to operate a vapor arc, means for cooling the interior of said anode and a heat insulating layer located between said cooled interior and the arc receiving surface of said anode.

2. A high powered mercury vapor rectifier containing anodes consisting of external and internal members which are separated from each other in part by an air space and in part by solid insulation, means for supplying a cooling fluid to said internal member and means cooperating with said external member to operate an electric arc.

3. An electrode structure comprising an

external current-conducting member and an internal member, said external member constituting the arc-receiving member of said structure, said members being provided with opposed surfaces separated a substantially constant distance from each other by a layer consisting of electrically and thermally poor conducting material, and means for directing a cooling fluid in contact with the internal member.

10 4. An electrode structure comprising an external current-conducting member and an internal member, said external member constituting the arc receiving member of said structure, said members being separated from each other by a chamber containing an electrically and thermally poor conducting material, and means for directing cooling fluid in contact with the internal member.

15 5. An electrode structure having an outer current-conducting wall and an inner wall, said outer wall constituting the arc-receiving member of said structure, said walls being spaced apart and of substantially the same 20 contour, electrical insulating material located between said walls, and means for directing a cooling fluid in contact with the inner wall.

25 6. An electrode structure comprising an external current-conducting member and an 30 internal member, said external member constituting the arc-receiving member of said structure, said members being provided with opposed surfaces substantially parallel with one another and insulated from one another 35 by means comprising a layer of electrically and thermally poor conducting material, and means for directing a cooling fluid in contact with the internal member.

30 In witness whereof, I have hereunto set
40 my hand this 6th day of October, 1923.

CHRISTIAN KRAMER.
